UNITED STATES PATENT OFFICE.

GEORGE E. SIBBETT, OF BERKELEY, CALIFORNIA.

TRACTOR-TREAD LINK.

1,338,402.

Specification of Letters Patent. Patented Apr. 27, 1920.

Application filed January 17, 1918. Serial No. 212,167.

To all whom it may concern:

Be it known that I, GEORGE E. SIBBETT, a citizen of the United States, residing at Berkeley, in the county of Alameda, State of California, have invented a new and useful Tractor-Tread Link, of which the following is a specification in such full and clear terms as will enable those skilled in the art to construct and use the same.

10 This invention relates to a link for tractor treads, and its object is to produce a link which will not tend to collect the sand and gravel as is commonly the case with such chains.

15 Another object of the invention is to provide means whereby the link will be provided with a heel piece which will prevent the chain from bending in one direction thereby dispensing with the large number 20 of rollers ordinarily used on such treads.

Another object of the invention is to provide means whereby the individual growers will be movable laterally through a slight angle thereby enabling the tractor chain 25 to pass over uneven ground without such great strains being placed upon the same as commonly occurs when the growers are rigidly connected with the chains.

Other objects of the invention will appear 30 as the description proceeds.

An embodiment of the invention is shown in the drawings in which the same reference numeral is applied to the same portion throughout, but I am aware that there may be modifications thereof.

Figure 1 is a perspective view showing a portion of the frame of the tractor, and a portion of the chain used therewith,

Fig. 2 is a side elevation of one of the complete tractor chains and of the wheels and frame-work supported by the chain,

Fig. 3 is an end view of one of the tractor links in transverse vertical section, and also illustrating one of the intermediate rollers bearing upon the same,

Fig. 4 is a side elevation of one of the links,

Fig. 5 is a plan view of one of the links,

Fig. 6 is a bottom plan view of one of the links,

Fig. 7 is an end view of one of the links looking from the left Fig. 4.

Fig. 8 is an end view of one of the links

looking from the right Fig. 4 and showing a growser plate attached thereto.

55

Fig. 9 is a plan view of one of the connecting pins, and

Fig. 10 is an end view of one of the connecting pins.

It will be understood by those skilled in the art that commonly tractors of the endless chain type have a pair of chains resting upon the ground, but in the present instance only the frame-work at one side of the tractor is shown, and in this drawing 65 the numeral 1 represents one of the side frames, 2 the other side frame, which frames are connected together by means of angle plates 3 and 4, and they may be connected to other parts of the tractor not shown by 70 any suitable connections.

At one end of the frame there are two sprocket wheels 5 and 6 revoluble on a shaft 7 journaled in boxes 8 and 9.

At the opposite end of the frame there 75 is a plain flanged wheel 10 around which the chain 11 passes.

Below the frame-work consisting of the parts 1 and 2 are brackets 12 and 13 which support flanged wheels 14 and 15, said 80 wheels bearing upon the top of the chain of the links providing an extended contact of said chain with the ground. The chain comprises a series of links having vertically extending web members 16 and 17, which 85 web members are connected at their top by an overhanging cover or plate 18. Said members 16 and 17 merge at one end into two eyes 19 and 20, and at the other end into a single eye 21 which exactly fits the space 90 between two of the eyes 19 and 20 upon the next adjacent length. The eye 21 is provided with a heel projection 22, which is adapted to be inserted under the top portion 18 when the chain is assembled to prevent the chain from bending upwardly between the two rollers 14 and 15. About 95 the center of the link there is a transversely extending web 23 which web has flanges 24, 25 for a purpose presently to be explained. 100

The growser plates so called are the plates which come in actual contact with the ground, and are indicated at 26, and they each have two projecting ears 27 which bear upon the lower side of the flanges 24, 25, 105 and are loosely held in position against the

same by means of the pin 28. The growser plates overlap each other slightly as indicated in Figs. 1 and 2, but as the unevenness of the ground causes them to move from 5 side to side, the entire series of growser plates in contact with the ground moves slightly. The eye 20 has a pocket formed therein at 30, the object being to receive the lug 31 on the pin 32, said pin being held in 10 place by means of a small bolt 33 passing through one of the walls of the link.

The principal advantage of this type of link lies in the fact that it has two driving surfaces at opposite ends of the pin 32 there- 15 by giving great wearing capacity, and in the use of the flanged rollers 14 and 15 which bear upon flat surfaces and do not tend to crowd the dirt and rocks into the body of the link, whatever dirt may ac- 20 cumulate being crowded off the chain.

Having thus described my invention what I claim as new and desire to secure by Let-

ters Patent of the United States is as fol-
lows:

1. A link for endless chain tractors comprising a flat bearing plate having a pair 25 of flanges extending therefrom, said link having a single eye at one end and a double eye at the other end for connecting to the next adjacent links, and a growser plate 30 pivotally connected with the link on an axis parallel to the length of the link.

2. A link for endless tread tractors comprising a flat bearing plate having a pair of flanges extending therefrom, said link hav- 35 ing a single eye at one end and a double eye at the other end for connecting to the next adjacent links, a transverse web connecting the two flanges adjacent their central portions, and a growser plate pivotally 40 connected to the said transverse web.

In testimony whereof I have hereunto set my hand this 7th day of January, A. D. 1913.

GEORGE E. SIBBETT.
